ABSTRACT

A decorative device has a horizontal base with a plurality of hollow elongated upwardly extending yieldable members secured at bottom ends to the base. The members resemble stalks of a plant. Very small incandescent lamps are disposed in the upper ends of the members. Wires in the members and base supply electricity to the lamps which can flash on and off.

FIG.1

FIG.2

FIG.3

DECORATIVE DEVICE

SUMMARY OF THE INVENTION

This invention is directed toward a decorative device employing light for display rather than illumination. The device employs a horizontal base with a plurality of hollow elongated upwardly extending yieldable members secured to the base at bottom ends. The upper end of each member is provided with a socket or other means for receiving a very small incandescent lamp. Wiring in the members and base connects the sockets to a source of electricity whereby the lamps in the socket are engaged.

The members resemble stalks of a plant. The lamps can be of conventional type which remains lit when energized or of other conventional type which flashes on and off when energized. Alternatively, suitable flasher units can be connected in the wiring whereby the type of lamps which remain lit when energized can be used, the units turning same on and off.

The flashing lights enhance the appearance of the device.

BRIEF DESCRIPTION OF THE DRAWINGS

In the drawings:

FIG. 1 is a perspective view of the invention
FIG. 2 is a circuit diagram thereof; and
FIG. 3 is a detail view thereof.

DETAILED DESCRIPTION OF PREFERRED EMBODIMENTS

Referring now to FIGS. 1-3, a horizontal rectangular base 10 is formed in successive tiers of decreasing area. Elongated hollow flexible plastic tubes 12 are secured at lower ends to the base and have lamp sockets 14 or other equivalent means in upper ends. A small incandescent lamp 16 is removably disposed in each socket.

Wiring 18 in each tube and in the base connects all sockets in parallel through corresponding flasher units

20, one for each socket, and rheostat 22 to a plug 24 adapted to be disposed in a wall or floor outlet to receive alternating or direct current. Rheostat 22 controls light intensity. The lamps flash on and off.

5 A vertical post 24 extends upward from the base and is surmounted by a ball 26 of aluminum foil to provide an additional element of unique appearance.

While the invention has been described with detailed reference to the drawings, the protection sought is to be limited only by the terms of the claims which follow.

I claim:

1. A decorative device comprising:

a horizontal base;
a rigid vertical member extending upwardly from the base;
a large ball of foil surmounting the top end of the rigid member to resemble a part of a plant;
a plurality of hollow elongated upwardly extending yieldable solid members secured at their bottom ends to the base and having open top ends, said yieldable member resembling the stalks of a plant and cooperating visually with the rigid member and foil to resemble a plant;

a like plurality of incandescent lamp sockets, each socket being disposed in a top open end of a corresponding member and extending along the longitudinal direction thereof;

a like plurality of extremely small incandescent lamps, each lamp being removably disposed in a corresponding socket and likewise extending in the longitudinal direction of the corresponding member; and means for supplying electricity to the lamps to energize them, the means including electric wiring in the base and in the individual members.

2. The device of claim 1 wherein each lamp flashes on and off.
